UNITED STATES PATENT OFFICE.

CHARLES E. FRANCIS, OF CINCINNATI, OHIO.

GLUE-SPREADER.

SPECIFICATION forming part of Letters Patent No. 655,482, dated August 7, 1900.

Application filed November 16, 1899. Serial No. 737,212. (No model.)

To all whom it may concern:

Be it known that I, CHARLES E. FRANCIS, a citizen of the United States, and a resident of Cincinnati, Hamilton county, State of Ohio, 5 have invented certain new and useful Improvements in Glue-Spreaders; and I do declare that the following is a description thereof so clear, full, and exact as to enable others skilled in the art to which it appertains to 10 make and use the same, attention being called to the accompanying drawings, with the reference-numerals marked thereon, which form also a part of this specification.

This invention relates to machines used in 15 woodworking, and particularly to such whereby glue is applied to larger surfaces of wood when such latter is to be connected by gluing. The glue is usually applied by rolls partly immersed, dipping into, or being otherwise in 20 contact with liquid glue contained in suitable receptacles, and from which latter the glue is taken up by the absorptive surfaces of the rolls and thereby transmitted to the wood while this latter passes through the machine.

25 The leading feature of my invention is a glue-spreader so constructed as to permit it to be used either to apply glue at the same time to the two opposite surfaces of a piece of wood, plank, board, &c., or only to one side 30 thereof.

Another feature is the use of a pressure-roll 35 coacting with a glue-spreader roll when glue is applied to one surface only at a time.

There are also features of construction in 40 general and in detail, all of which will be more fully set forth hereinafter.

In the following specification and particularly pointed out in the claims at the end thereof is found a full description of my invention, 45 together with its operation, parts, and construction, which latter is also illustrated in the accompanying drawings, in which—

Figure 1 is an end view of the machine. 45 Fig. 2 is a vertical section of the upper part of the machine, taken on a line back of Fig. 1. Fig. 3 is a view similar to Fig. 1, showing the opposite end of the machine. Fig. 4 is a vertical section of the upper part of it, taken on 50 a plane back of Fig. 3. Fig. 5 is a front view of the machine. Fig. 6 is a section on line 6 6 of Fig. 1. Fig. 7 is an enlarged detail view,

partly in section, of the means for adjustably supporting the upper roll.

8 is the lower and 9 the upper glue-spreader 55 roll, consisting each of a suitable core, the outer surface of which is rendered sufficiently absorptive to enable it to take up glue and transfer it to the surface of the wood. In the present case this absorptive surface is obtained by covering the core with a material like cloth or carpet. The journals of the lower roll are mounted in boxes 11, while those of the upper one are carried in boxes 12.

13 is the glue-tank for the lower roll, being 60 surrounded by a customary jacket 14, the space between the two being filled with hot water or steam, which is kept in circulation and serves to maintain the glue in proper condition. The latter is supplied by a gutter 70 15 from a suitable glue-supply tank or boiler, (not shown,) while the steam circulates through pipes 16 and 17. The glue-tank may be emptied entirely through an outlet 18.

Figs. 1 and 2 show the machine used for 75 applying glue at the same time to two opposite surfaces, for which purpose the upper roll is moved down toward the lower one and properly adjusted with reference to the thickness of the wood which is to pass between 80 them. For purposes of such adjustment the boxes of the upper roll are connected each to a screw 19, upon each of which is also mounted a nut 21. These latter by means of collars 22 are prevented from moving longitudinally 85 on screws 19, but are free to rotate about them, which rotation causes such screws to either rise or fall, carrying with them boxes 12 and the upper roll mounted therein. During such movement these boxes are guided by 90 the machine-frame to which they are fitted.

Nuts 21 are operatively connected to each other by means of bevel-gears 23 and a shaft 24, mounted in brackets 25, so that they may be simultaneously rotated. For the necessary 95 manipulation a hand-wheel 26 is provided on one of the nuts. The position of the rolls is not absolutely rigid, but permits a limited automatic adjustment of the space between them and through which the wood passes to 100 accommodate any irregularities in the thickness of this latter, as well as to have said wood engaged by a live pressure for the purpose of moving it. All this is obtained by

connecting the lower ends of the screws 19 loosely to boxes 12 and interposing springs 27 at the points of connection. The details of this construction are as follows:

- 5 The upper part of each box 12 is recessed and part of each recess is closed by a collar 28, held in place by a set-screw 29. The lower ends of screws 19 are reduced in diameter and pass loosely through an opening in the 10 collars, below which they are each provided with a shoulder 30 to prevent disengagement of the parts. Some distance above there is another shoulder 31, and between it and the boxes below said springs 27 are confined.
- 15 It will now be seen that for purposes of mere support and for positive movement during adjustment boxes 12 are rigidly connected to the lower ends of the adjusting-screws; but for the purpose of an automatic 20 adjustment the upper roll is capable of yielding upwardly to an extent equal to the depth of the space below shoulder 30. The upper shoulder 31 is preferably in shape of a nut, being thus rendered movable in position and 25 permitting adjustment of the pressure of the springs. By means of a key and groove or by shaping a portion of the screws otherwise than round these latter are prevented from turning while nuts 21 are manipulated, which 30 portion or key and groove is preferably placed at the point where screws 19 pass through collars 28.

The upper glue-roll 9 is supplied from a trough 32, supported in front of it and lying 35 across the face thereof, its side toward this latter being removed and its place taken by opposite parts of the face of roll 9, against which latter the glue constantly lies, and is thus conveyed thereonto. The other 40 side and the bottom of this trough are jackeded, as shown at 33, the space between being filled with hot water or steam circulating through pipes 34 and 35, whereby the glue is kept in proper consistency. This trough is 45 preferably formed of a hollow casting, shaped as shown, and the ends of which are closed by heads 36. It is supported by two brackets, being fitted between dovetailed slides 38 thereon and on which it is adjustable to or 50 from roll 9, being held in its adjusted position by set-screws 39, passing through slots in the brackets. By means of adjusting-screws 34, mounted immovably, except as to rotation, at the ends of the trough and engaging stationary nuts 42 at the ends of brackets 37, this trough may be moved to and from the 55 face of roll 9 for the adjustment mentioned, thereby regulating the amount of glue supplied to this latter, edge 43 of the trough 60 acting as a scraper for such purpose. Brackets 37, which carry this glue-trough, are secured to or form part of boxes 12, which support the upper glue-roll, so that this latter in all of its adjustments carries its glue- 65 supply constantly with it. A gutter 44 supplies this trough from the same source which supplies tank 13. Any excess in the former

overflows to the latter through a pipe 45. The wood is advanced through the space between the glue-rolls by frictional contact, said glue-rolls being positively rotated for such purpose. The power is supplied at one end of the lower glue-roll in any suitable way—as, for instance, by a pulley 46. From here the power is transmitted to the upper glue-roll by means 75 of sprocket-wheels 47, mounted at the other ends of each of the rolls and connected by a chain 48.

49 and 51 are idler guide pulleys, which support the chain in a manner to guide its 80 movement in the proper direction. This latter pulley being adjustably supported on a bracket 52 serves also as a tightener to keep the chain taut.

If it is desired to use the machine for applying glue on one side only of the wood, then the upper glue-roll and its trough are raised by means of screws 19, operated by hand-wheel 26. The necessary pressure to hold the wood against the lower glue-roll is now 90 supplied by a pressure-roll 53, hitherto unused and occupying a position out of the way, as shown in Figs. 1 and 2. This roll is carried between arms 54, pivoted on brackets 55, forming also projecting parts of boxes 12, and 95 is now swung down to a position as shown in Figs. 3, 4, 5, and 6, and in which position it is held by links 56, which are connected each with one of their ends to arms 54 and with their other ends to brackets 37. This latter 100 connection is by hand-screws 57, which permits quick and convenient disconnection or reattachment to change the machine to one operating either with a double or with a single glue-roll. After such adjustment for the 105 purpose as just described and during the time while so operated boxes 12, brackets 37, brackets 55, links 56, and arms 54, between which the pressure-roll is supported, form all a rigid structure held and adjusted by screws 110 19 subject to the action of the yielding adjustment by springs 27. At this time also the supply to the upper tank is stopped and chain 48 is preferably entirely removed, which may be readily done by moving idler 51 to 115 render the chain sufficiently slack. To permit such movement of this idler, the stud-shaft on which it is mounted is connected to bracket 52 by means of a screw connection, as shown at 58. When the pressure-roll is 120 up, as shown in Figs. 1 and 2, it is held so by lugs 59, engaging and resting upon the upper edge of brackets 55 or of boxes 12. The amount of glue to be taken up by the lower roll is regulated by a scraper 61, adjustably connected by set-screws 62 to one of the upper edges of the lower tank. The whole machine above this latter may be tipped for access, for which purpose the machine-frame is hinged at 63, while otherwise it is held 130 locked by means as shown at 64.

65 is a faucet, by means of which hot water may be obtained for use in regulating the consistency of the glue within the tank.

Having described my invention, I claim as new—

1. In a glue-spreader, the combination of a machine-frame, glue-applying rolls with a glue-supplying receptacle for each supported thereon, said rolls being adjustable to or from each other, a pressure-roll and means whereby it is connected to the machine-frame in a manner to be capable of occupying either an inoperative position or one in which it acts in conjunction with one of the glue-applying rolls.

2. In a glue-spreader, the combination of two glue-applying rolls supported in a manner to permit adjustment of the space between them, a glue-supplying receptacle for each, and a pressure-roll adjustably supported in a manner to permit it to occupy positions, either within the space between the two glue-applying rolls, or one outside of such space.

3. In a glue-spreader, the combination of two glue-applying rolls, one above the other, boxes in which they are supported, screws at-

tached to the boxes of the upper roll whereby this latter may be adjusted with reference to the lower one, a glue-trough and a pressure-roll, brackets, one on each side of the machine to which both are connected for support and which brackets are attached to the boxes of the upper glue-roll, the connection of the pressure-roll being an adjustable one, which permits change in position from one inoperative to one in which it acts in conjunction with the lower glue-roll and means to fixedly hold the pressure-roll in either one of its positions.

4. In a glue-spreader, the combination with a glue-applying roll of the hollow trough-casting 32, shaped, as shown, to form a bottom 40 and a side of the trough with a jacket therefor and having its ends closed by heads 36.

In testimony whereof I hereunto set my hand in presence of two witnesses.

CHARLES E. FRANCIS.
